DECORATIVE HANGING DISPLAY SHELF

Darwin L. Seamons, South Gate, Calif.

Application November 24, 1958, Serial No. 53,511

Term of patent 14 years

(Cl. D29—23)

Fig. 1 is a perspective view of a decorative hanging display shelf showing my new design.

Fig. 2 is a reduced plan sectional view taken on the line 2—2 of Fig. 1 with the container elements attached to the bottom shelf being omitted for convenience of illustration.

Fig. 3 is a fragmentary bottom plan view of the under side of the top shelf.

The dominant features of my design reside in the portions shown in full lines.

I claim:

The ornamental design for a decorative hanging display shelf, substantially as shown and described.
